UNITED STATES PATENT OFFICE.

ERNST SENSBURG, OF MUNICH, GERMANY.

TYPE-WRITER.

SPECIFICATION forming part of Letters Patent No. 664,590, dated December 25, 1900.

Application filed November 2, 1900. Serial No. 35,289. (No model.)

To all whom it may concern:

Be it known that I, ERNST SENSBURG, a subject of the King of Bavaria, residing at Munich, Kingdom of Bavaria, Germany, have invented certain new and useful Improvements in Type-Writers, of which the following is a full, clear, and exact description.

My invention relates to improvements in type-writing machines.

10 The object of my invention is to provide a type-writing machine which while reasonably compact will permit of the use of a larger number of type than usual, so that not only letters may be printed at one stroke of a key, but also syllables and words such as are in common use.

With this object in view and some others which will be obvious to those skilled in the art a machine embodying my invention comprises a plurality of type-bar carriers or frames mounted on a carriage, each provided with a plurality of type-bars, each of which type-bars carries a plurality of type, means being provided for positioning the type-bar carriers with relation to the printing-point and for positioning any desired type-bar of the positioned carrier, whereby the desired type on the type-bar is brought to the printing-point. Any suitable paper carrying and feeding mechanism may be employed and also any kind of spacing device or printing mechanism.

35 My invention will now be described in connection with the drawings and then particularly pointed out in the claims.

In the drawings, Figure 1 is a side elevation of so much of a machine embodying my invention as is necessary to illustrate the said invention; Fig. 2, a plan view of the same; 40 Fig. 3, a detail perspective view of one of the type-bar carriers or frames with the type-bars, showing also a part of the means for positioning the type-bars.

Referring to the drawings, $b' b^2 b^3 b^4$ indicate a plurality of type-bar carriers or frames (in the present case four in number) mounted in a carriage B, movable along a track B'. Each frame or carrier $b' b^2 b^3 b^4$ is provided with a set of type-bars, each set consisting of 50 a plurality of movable type-bars, in this instance three in number, as indicated at $a' a^2 a^3$, Fig. 3, each of which has a plurality of

type, as indicated at a, Fig. 3. The type-bars $a' a^2 a^3$ are mounted to move in the respective carrier in the direction of their own lengths, for example, by providing slots in the frame in which the said type-bars lie, the said type-bars being held in the slots in a manner to permit of their longitudinal movement by any suitable means—as, for example, by undercutting the slots and making the type-bars of a corresponding cross-section, so that they will properly fit said slots. The sets of type-bars are so arranged in their respective frames that the axes of the type-bars of each set will intersect at the printing-point. For example, in the structure shown in Fig. 3 the central type-bar a^2 occupies a vertical position, while the two outer type-bars $a' a^3$ are each arranged at an angle to the central type-bars, so that the axes of the type-bars would intersect at the point x, Fig. 3, which is the printing-point. By this construction any desired type on any one of the type-bars may be brought to the printing-point by moving the proper bar in the direction of its length for a suitable distance. Furthermore, by moving the carriage B, containing the frames b' to b^4 , in the proper direction and to the required extent any desired set of type-bars may be brought into the plane of the printing-point, whereby any desired type of any type-bar in any of the various sets may be positioned for printing.

In the machine under consideration the 85 normal position of the type-bars $a' a^2 a^3$ is with their upper ends below the printing-point, and hence in order to position a type for printing the bar carrying the desired type must be elevated. Therefore in the present 90 machine I provide means for moving the carriage B and means for elevating the type-bars. The preferred mechanism for doing this will now be described.

The carriage B, Fig. 1, is connected in a 95 suitable manner to the upper end of a lever e by means of a pin e', secured to the carriage, which pin enters a slot in the end of the lever e. The latter is fulcrumed on the frame, as at e^2 , and is arranged to be moved in any suitable manner—as, for example, by a treadle-lever E, connected by a link E' to a bell-crank E², which is joined by a rod E³ to the lower end of the lever e.

In order to elevate the type-bars when the latter are in the plane of the printing-point, each type-bar may be provided with a depending lifter-rod $r' r^2 r^3$, Fig. 3, each rod being

- 5 connected to its respective type-bar by a loose connection—such, for example, as a ball-and-socket joint (indicated at S, Fig. 3)—each rod being forced outward at an angle by means of a spring $u' u^2 u^3$, secured at one end to its
- 10 respective rod and at the other end passed loosely through a staple R on the end of the type-bar. In order to prevent the springs $u' u^2 u^3$ from forcing the rods outward unduly and to insure the normal retention of the rods,
- 15 at a predetermined angle to the type-bars, suitable stop devices are provided, these consisting, preferably, either of a loop secured to the type-bar, as shown at t^2 in Fig. 3, or of fingers $t' t^3$, which are secured to the respective type-bars and extend over the corresponding rods. By this means the lower ends of the rods $r' r^2 r^3$ may be held in a line with each other. The said lower ends are arranged to be engaged by suitable lifting devices—as, for
- 20 example, the key-levers $o' o^2 o^3$ —each of which is fulcrumed in the frame, as indicated at O, Fig. 1, and is provided with a socket O' , arranged to engage a ball on the lower end of the corresponding lifter-rod.
- 25 30 For the purpose of operating the levers $o' o^2 o^3$ the predetermined extent necessary to bring the various types to the printing-point a number of plunger-keys $p' p^2 p^3$, Fig. 2, are provided, these keys being preferably arranged in banks, as shown in Fig. 1, each bank being at a different distance from the fulcrum of its corresponding lever $o' o^2 o^3$, each lever being provided with lateral arms q , which are engaged by the key-plungers when the latter are depressed.

The paper to be printed may be mounted and moved in any desired way, this part of a complete type-writing machine forming no essential part of my present invention. In 45 Fig. 1 I have indicated in a general manner one form of such mechanism in which the paper is mounted on one roll h and led to another roll k over two guide-rollers g and i , so that a certain portion of the paper will be 50 brought parallel to the plane of the printing-point and opposite the latter. The said paper rolls and rollers are mounted on any suitable carriage, as indicated at f , Fig. 1, capable of movement across the machine in the 55 normal way. Any desired form of ink-supplying mechanism may be provided, and the printing, which is done by striking the paper against the inked type or against an inking-ribbon interposed between the type and paper, may be accomplished by any suitable mechanism such as is well known in the art. For example, I have shown a longitudinally-movable rod m arranged to strike the paper against the type, and thereby produce an impression, which rod m may be moved at the proper time in any suitable way.

The operation of the machine just described

is as follows: The operator ascertains by inspection upon which keyboard is located the key for the character desired to be printed and then presses the treadle-lever to the extent necessary to bring the frame or carrier containing the type for such character to the plane of the printing-point. He then presses down the proper key, and thereby elevates the corresponding type-bar, the motion transmitted from the key to the type-bar being just sufficient, when the key is fully pressed down, to bring the desired type to the printing-point. At this moment the rod m is operated to force the paper against the positioned type, whereby an impression of the desired character is made upon the paper. Succeeding characters are printed in the same way, it being understood that the paper is fed in the proper direction and to the required extent by suitable mechanism at the proper time.

As each key serves to position a series of type-bars—viz., one type-bar on each frame—and as each of said type-bars is intended to carry different type, it is clear that each key will serve for positioning a plurality of type characters. Hence it will be preferable to have each of said characters which a key will 95 position marked on said keys. One key so marked is shown on the middle keyboard in Fig. 2.

While I have described and shown a machine having four type-bar carriers or frames, each of which is provided with three type-bars, it is to be understood that I do not limit my invention to these specific numbers of carriers or type-bars.

Having thus fully described my invention, what I claim, and desire to secure by Letters Patent, is—

1. In a type-writer, the combination with a plurality of type-bar carriers and type-bars bodily and vertically movable therein, each type-bar having a plurality of type, of means for moving the carriers to the plane of the printing-point, and means for moving the type-bars relative to the carriers to bring the desired type on the type-bar to the printing-point.

2. In a type-writer, the combination with a plurality of type-bar carriers, a carriage on which the same are mounted, and type-bars bodily movable in the carriers and provided with a plurality of type, of means for moving the carriage to bring the type-bar carriers to the plane of the printing-point, and means for moving the type-bars, whereby the desired type may be brought to the printing-point.

3. In a type-writer, the combination with a plurality of type-bar carriers, and a plurality of sets of type-bars, one set movably mounted in each carrier, the type-bars of each set being so arranged that their axes will intersect at the printing-point, of means for positioning the carriers and means for positioning the type-bars.

4. In a type-writing machine, the combination, with a horizontally-movable carriage, a plurality of type-bar carriers mounted therein, and means moving the carriage to position the type-bar carriers, of a plurality of vertically-movable type-bars mounted in each type-bar carrier, each type-bar having a plurality of type, and means for positioning the type-bars.

5. In a type-writing machine, the combination with a type-bar carrier, of a plurality of type-bars movably mounted in said carrier, a lifter-rod connected to each type-bar, and means for engaging the lifter-rod when its respective carrier has been positioned.

6. In a type-writing machine, the combination with a plurality of type-bar carriers, of a plurality of sets of type-bars, one set mounted in each carrier, each type-bar having a plurality of type, a lifting-rod connected to each type-bar, a set of actuating devices, and means for moving the type-bar carriers to bring any desired carrier with the lifting-rods of its set of type-bars into a position for engagement by the actuating devices.

7. In a type-writer, the combination with a type-bar carrier, and a plurality of type-bars movably mounted therein, each type-bar having a plurality of type, of a lifter-rod flexibly connected to each type-bar, and means for engaging the lifter-rods to position the type-bars.

8. In a type-writer, the combination with a type-bar carrier, and a type-bar movably mounted therein and provided with a plurality of type, of a lifter-rod flexibly connected to the type-bar, a spring arranged to hold the lifter-rod at an angle to its type-bar, and means for engaging the lifter-rods to position the type.

9. In a type-writer, the combination with a type-bar carrier, and a type-bar movably mounted therein and provided with a plurality of type, of a lifter-rod movably connected to the type-bar, means for holding the lifter-rod at a predetermined angle to the type-bar, a lever arranged to engage the lifter-rod, and means for operating the lever, whereby the type-bar is positioned.

10. In a type-writer, the combination with a series of type-bar carriers, and type-bars mounted to slide in a vertical plane therein, of a carriage to support the said type-bar carriers, and means for moving the carriage to bring any one of the said type-bars into position to print when actuated by the keys of the type-writer.

In witness whereof I have hereunto set my hand in presence of two witnesses.
